United States Patent Office

Des. 188,384
Patented July 12, 1960

188,384

FLOWER HOLDER

Wanda Messer, 4009 E. Patricia Jane Drive,
Phoenix, Ariz.

Filed Aug. 6, 1958, Ser. No. 52,069

Term of patent 14 years

(Cl. D35—3)

Des. 188,384

PAGE 2

FIG. 2.

Fig. 1.

The characteristic features of my design for the flower holder disclosed resides in the base having the appearance best shown in Fig. 3 of the drawing.

I claim:

The ornamental design for a flower holder, as shown and described.
